UNITED STATES PATENT OFFICE.

ANDREW J. CORCORAN, OF JERSEY CITY, NEW JERSEY.

WINDMILL.

SPECIFICATION forming part of Letters Patent No. 387,212, dated August 7, 1888.

Application filed November 16, 1887. Serial No. 255,368. (No model.)

To all whom it may concern:

Be it known that I, ANDREW J. CORCORAN, a citizen of the United States, residing at Jersey City, in the county of Hudson and State 5 of New Jersey, have invented certain new and useful Improvements in Windmills; and I do hereby declare the following to be a full, clear, and exact description of the same, reference being had to the accompanying drawings, 10 which form a part of this specification.

This invention relates to certain new and useful improvements in windmills, and has for its object to provide a windmill that will be both strong and light in construction, and be 15 capable of resisting the force of the wind without liability of the parts becoming disarranged or broken; and it consists in the construction and arrangement of parts hereinafter described, and then specifically pointed out in 20 the claims, due reference being had to the accompanying drawings, forming a part of this specification, wherein—

Figure 1 is a front elevation of my improved windmill, a portion only of the blades being 25 shown; Fig. 2, a vertical central section of a portion thereof; Fig. 3, a top view of one of the clips employed for securing together one of the radial arms and two of the section-bars and adjustably holding one end of one of the 30 stay-rods; Fig. 4, a vertical central section thereof; Fig. 5, a top view of a clip employed for securing the outer section-bars to the radial arms; Fig. 6, a vertical central section thereof; Figs. 7 and 8, perspective views of said clip; 35 Figs. 9 and 10, perspective views of the clip shown in Figs. 3 and 4; Fig. 11, an end view of the clip shown in Figs. 5, 6, 7, and 8; and Fig. 12, a detail view showing how the radial arms and the ends of the section-bars are joined 40 together. Fig. 13 is an enlarged detail view of the boss K and the ends of the stay-rods H, fastened thereto; and Fig. 14 is a section on the line $\alpha\alpha$, Fig. 2, looking from the center of the wheel outward.

Referring to the drawings, the letter A denotes the wheel-shaft; B, the spider; C, the 45 radial arms; D D', the section-bars, and E the blades secured to the section-bars in the usual manner. The spider B is mounted upon the 50 wheel-shaft, as usual, and consists of two an-

nular flanges or hubs bolted together, and between which are secured the inner ends of the radial arms C. For the purpose of affording additional strength to the wheel, I bolt to the radial arms, near the spider, an annular collar, F.

G indicates the clip for securing together the radial arms and the inner section-bars. As more clearly shown in Figs. 3, 4, 9, and 10, this clip consists of a casting having a base or web, g , from each side of which rise arms $g'g'$, which are bridged over at the top by the cap g^2 . This construction forms a rectangular opening in the casting, through which passes one of the radial arms C of the wheel. The 65 base or web g of the casting is provided upon each side with lugs g^3g^3 , from which rise flanges g^4g^4 , as more clearly shown in Fig. 10, which, in connection with the cap g^2 , receive and support the ends of the section-bars D. From the 70 cap g^2 of the casting rises an ear, g^5 , having an inclined perforation, g^6 , for the reception of one end of the stay-rod H, and said ear g^5 is provided with a screw-threaded perforation, g^7 , at a right angle to the perforation g^6 , which receives a set-screw, g^8 , which is adapted to be screwed down upon the stay-rod H and hold the same tightly in place. All of the above-mentioned parts of the casting excepting the set screw g^8 are cast integral.

In assembling the parts above described the radial arms C are first firmly secured in place between the hubs composing the spider B and bolted in place, and the annular collar F bolted to said arms. The clips G are next slipped 85 onto the radial arms, and the section-bars D placed in position between the radial arms, the ends of the section-bars being rabbeted to receive the radial arms, as shown in Fig. 12. The clips G are now forced up into place till 90 the ends of the section-bars D are closely embraced by the clips, as shown in the drawings. The clips are then secured in place by bolts 1 1, which pass through bolt-holes in the web of the clip and through holes bored in the radial arms, and are fastened by means of nuts.

It will be seen that the radial arms and the section-bars are closely united by means of the clips G without the use of fastenings other than the bolts 1 1, and will effectually resist 100

both the force of the wind and that exerted by centrifugal motion resulting from the rapid rotation of the wheel.

I indicates the clip employed for uniting the outer section-bars, D' D', to the radial arms C. As shown in Figs. 5, 6, 7, 8, and 11, this clip is composed of a casting having a flat web or bottom, *i*, of the shape shown in Fig. 8, from which rises a V-shaped flange, *i*², of a shape to embrace the sides of the meeting ends of the section-bars D' D', and said web *i* is also provided upon each side with a flange, *i*³, to embrace the sides of the radial arm C. In connection with this clip I, I employ a slightly V-shaped strut, *i*⁴, said strut being provided at each end with a suitable bolt-hole, the web *i* of the clip I being provided with two corresponding bolt-holes and two other bolt-holes adapted to register with two bolt-holes in the radial arm C, as will hereinafter appear. The V-shaped flange *i*² of the clip I is provided with a rectangular aperture extending upwardly from the web *i*, as shown, of a size and shape to admit the passage of the radial arm C.

In uniting the section-bars D' D' to the radial arm C, the said section-bars are first placed in position, their ends being rabbeted to receive the radial arms similarly to the section-bars D, before described, and the clips are next forced inwardly over the radial arms until the V-shaped flanges *i*² closely embrace the ends of the section-bars. The clip is then secured in place by means of bolts 2 2, which are passed through bolt-holes in the web *i* of the clip and through corresponding holes made in the radial arm, and fastened by means of nuts. The strut is next placed on top of the meeting ends of the section-bars D' D', as shown in Figs. 5 and 7, and secured in place by means of bolts 3 3, which pass through bolt-holes in the ends of the strut and through corresponding bolt-holes made in the section-bars and in the web *i* of the clip, the bolts being fastened by means of nuts.

The stay-bars H are secured in place as follows: Upon the outer end of the wheel-shaft A is mounted an annular boss, K, within or to which are secured in any suitable manner the inner ends of the stay-bars H. The outer ends of said stay-bars are passed through the inclined perforations *g*⁶ of the clips G, and are adjustably held therein by means of the set-screws *g*⁸. The stay-bars are preferably thus secured in place at the same time the clips G are bolted in position. By fastening the outer ends of the stay-rods H adjustably in place any warping or shrinking of the wheel which may

occur from time to time may be compensated for.

Having thus described my invention, what I claim is—

1. In a windmill, the combination, with the wheel-shaft, the radial arms, section-bars, and stay-rods, of a clip for securing said arms and section-bars together, provided with an adjustable holding device, substantially as described, for securing the ends of the stay-rods.

2. The clip G, for securing the section-bars to the radial arms, comprising a web, *g*, arms *g*' *g*', cap *g*², lugs *g*³ *g*³, and vertical flanges *g*⁴ *g*⁴, the said clip adapted to be slipped over the radial arms and embrace the ends of the section-bars and fastened in place upon the radial arms by bolts, substantially as shown and described.

3. The clip G, for securing the section-bars to the radial arms, comprising a web, *g*, arms *g*' *g*', cap *g*², lugs *g*³ *g*³, and vertical flanges *g*⁴ *g*⁴, and provided with a perforated lug for the reception of the stay-rod, and a set-screw for adjustably securing the stay-rod in place, substantially as shown and described.

4. The clip I, for securing together the radial arms and the section-bars, consisting of a web, *i*, a V-shaped flange, *i*², and a strut, *i*⁴, the V-shaped flange *i*² being provided with an aperture for the reception of the radial arm, the whole being secured in place by means of bolts, substantially in the manner shown and described.

5. The clip I, for securing together the radial arms and the section-bars, consisting of a web, *i*, a V-shaped flange, *i*², side flanges, *i*³, and a strut, *i*⁴, the V-shaped flange *i*² being provided with an aperture for the reception of the radial arm, the whole being secured in place by means of bolts, substantially in the manner shown and described.

6. In a windmill, the combination, with the wheel-shaft A, the annular boss K, mounted on the outer end thereof, the radial arms C, secured to the shaft by means of the spider B, and braced by the annular collar F, bolted to said arms, the section-bars D, and the stay-rods H, secured at their inner ends to the annular boss K and adjustably secured at their outer ends to the radial arms C, all constructed and arranged substantially as shown and described.

In witness whereof I have hereunto subscribed my name.

ANDREW J. CORCORAN.
